UNITED STATES PATENT OFFICE.

JOHN HOOD McCAMANT, OF GALLUP, NEW MEXICO.

CALF-WEANER.

1,325,795.

Specification of Letters Patent. Patented Dec. 23, 1919.

Application filed February 28, 1919. Serial No. 279,833.

To all whom it may concern:

Be it known that I, JOHN HOOD McCAMANT, a citizen of the United States, residing at Gallup, in the county of McKinley and State of New Mexico, have invented a new and useful Calf-Weaner, of which the following is a specification.

My invention is a non-destructible and adjustable calf weaner; and the objects of my invention are, first, to provide a durable calf weaner that may be used from year to year; second, to provide a calf weaner that can be adjusted to fit any calf; third, to provide a calf weaner that will not punish or torture the mother of the calf; fourth, to provide a calf weaner that will prevent the calf from sucking but will not prevent it from grazing; and fifth, to provide a calf weaner that cannot be broken or torn off or destroyed by the calf.

I attain these objects by the mechanism illustrated in the accompanying drawing, in which—

Figure 1 is a front view of the entire mechanism; Fig. 2 is a view of the iron pin which is located in the upper left hand part of the mechanism as shown in Fig. 1; Fig. 3 is a view of the iron tube which is located in the upper right hand part of the mechanism as shown in Fig. 1; Fig. 4 is a view of the adjustable screw pin which fits and screws into the iron tube shown in Fig. 3; Fig. 5 is a sectional view taken on the broken line 4—4 of Fig. 1.

The plate 1 is cut in the shape shown in Fig. 1 from galvanized iron; the upper left hand part being bent around and securely

soldered to the iron pin 2; the upper right hand part being bent around and securely soldered to the iron tube 3.

The iron tube 3 is threaded inside of the right hand end to a depth of one inch to accommodate the screw pin 4.

The set screw 5 fits into a threaded hole through plate 1 and iron tube 3 for the purpose of setting the screw pin 4 after it has been properly adjusted to fit the calf.

At 6 the screw pin is smooth, and at 7 it is threaded to engage the thread 8 in the tube 3. In the practical use of the weaner, the pin 2 is arranged at one side of the cartilage between the nostrils of a calf, and the screw pin 4 is adjusted between the opposite side of the cartilage, and hence it will be understood that the plate will drop over the mouth of the calf when the calf attempts to nurse, and will fall away from mouth when the calf seeks to graze, so that it will not interfere with such operation.

I claim:

A calf weaner comprising a sheet-metal plate having in one edge portion an opening and also having its portion at opposite sides of said opening shaped into aligned barrels, a pin secured in and projecting from the inner end of one barrel, a tube fixed in the other barrel and having an interiorly threaded outer end portion, and a screw pin threaded to engage the thread of the tube and having an inner end portion projecting from the inner ends of the tube and the barrel containing the tube.

JOHN HOOD McCAMANT.
